(57) **CLAIM**

The ornamental design for a modular basement shoring panel, as shown and described.

DESCRIPTION

FIG. 1 is a front perspective view of a modular basement shoring panel, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a magnified top plan view thereof.

The broken line portion of the figures is included to show unclaimed subject matter only and forms no part of the claimed design.
